D11-139. OR D13,439 EX

Design No. 13,439, dated November 21, 1882.

UNITED STATES PATENT OFFICE.

LIV. G. COLLINS, OF CHICAGO, ILLINOIS.

DESIGN FOR A WALL ORNAMENT.

SPECIFICATION forming part of Design No. 18,439, dated November 21, 1882.

Application filed October 3, 1882. Term of patent 3½ years.

To all whom it may concern:

Be it known that I, LIV. G. COLLINS, a citizen of the United States, residing in Chicago, in the county of Cook and State of Illinois, 5 have invented a new and original Design for a Wall Ornament, of which the following is a specification.

The accompanying illustration shows a view of my design for wall ornament. The same 10 consists of a sickle and sheaf of wheat tied together by a ribbon. I make the sickle of wood, paper, celluloid, ebonite, or sheet metal, preferring, however, to use white holly-wood of the kind commonly employed for making sawed 15 ornaments. The sheaf is made of natural wheat or other natural grass or grain, and is secured to the sickle by the ribbon shown in the illustration, or it may be secured by other or additional means. The plane surface of the

sickle, being suitably prepared, is adapted as a 20 ground-work for any desired ornamental painting or embellishment, and the whole device is intended to be sold to amateur painters, to be by them ornamented in any manner desired by painting on the surface of the sickle or the 25 ribbon.

I contemplate providing the device with means to suspend it upon the wall, which may consist of a cord, an additional ribbon, or a simple hole bored through the sickle. 30

I claim—

The design for wall ornament, consisting of the sickle, the sheaf, and the ribbon, combined and disposed substantially as specified.

LIV. G. COLLINS.
